DESIGN FOR A PENCIL TIP

Joseph McNulty, Bergenfield, N. J., assignor to Eagle Pencil Company, New York, N. Y., a corporation of Delaware

Application December 10, 1937, Serial No. 73,519

Term of patent 14 years

To all whom it may concern:

Be it known that I, Joseph McNulty, a citizen of the United States and residing at Bergenfield, New Jersey, have invented a new, original, and ornamental Design for a Pencil Tip, of which the following is a specification, reference being had to the accompanying drawing, forming part thereof, and in which—

Fig. 1 is a front elevation of the pencil tip showing my new design.

Fig. 2 is a side elevation of the pencil tip.

Fig. 3 is a top plan view of the pencil tip, and
Fig. 4 is a bottom plan view of the pencil tip.

I claim:

The ornamental design for a pencil tip, substantially as shown.
